UNITED STATES PATENT OFFICE

LEONARD C. BURNS, OF PORTLAND, OREGON

EXPANSIBLE PISTON

Application filed May 31, 1927. Serial No. 195,504.

This invention relates to certain new and useful improvements in expandable pistons or plungers and has for its object to provide, in a manner as hereinafter set forth, a piston or plunger, hereinafter termed a piston, of the class referred to constructed in a manner whereby it can be expeditiously expanded to meet requirements when the wall of a cylinder has become worn, under such conditions **10** overcoming the necessity of the employment of an oversized piston and the re-boring of the cylinder wall.

Further objects of the invention are to provide, in a manner as hereinafter set forth, an **15** adjustable expandable piston which is simple in its construction and arrangement, strong, durable, compact, thoroughly efficient in its use, conveniently adjusted and expanded when desired, readily assembled and comparatively inexpensive to set up.

With the foregoing and other objects in view the invention consists of the novel construction, combination and arrangement of parts, as hereinafter more specifically **25** described and illustrated in the accompanying drawings, wherein is shown an embodiment of the invention, but it is to be understood that changes, variations and modifications can be resorted to which fall within the scope **30** of the claims hereunto appended.

In the drawings wherein like reference characters denote corresponding parts throughout the several views:

Figure 1 is a vertical sectional view of a **35** piston, in accordance with this invention, in a normal position prior to the expansion thereof.

Figure 2 is a vertical sectional view of the piston adjusted to provide for the expansion **40** thereof.

Figure 3 is a plan view of the retainer plate.

Figure 4 is a plan view of one of the shims.

Figure 5 is an inverted plan view of one of the expanders.

Figure 6 is a cross sectional view of a modified form of expander.

An adjustable, expandible piston, in accordance with this invention, comprises a core referred to generally by the reference character 1 and formed of a cylindrical por-

tion 2 and a tapered portion 3, which at its larger end merges into the cylindrical portion **55** 2 and is inset with respect to the outer edge of said portion 2 thereby providing in connection with the latter a shoulder or seat 4 which extends entirely around the point of **60** emergence of the tapered portion 3 with the cylindrical portion 2. The rear end of the core 1 is formed with a concave recess 5 to provide a clearance for the operation of the piston rod 6. The recess 5 is of a depth less than half the length of the core 1 and extends through the portion 2 and for a short distance in the portion 3.

The tapered portion 3, of the core 1 is **65** formed with a transversely extending opening 7, which is intersected centrally thereof by a lengthwise extending rectangular slot 8, the latter merges at its forward end into an opening 9 which communicates with a socket **70** 10 at the forward end of the tapered portion 3. The slot 8, opening 9 and socket 10 are arranged at the axis of the core 1. The slot 8 is of greater length than the opening 9, of a length greater than the depth of the socket **75** 10 and opens at its rear end into the recess 5. The diameter of the opening 9 is less than the width of slot 8 and socket 10.

The head of the rod 6, indicated at 11, is positioned within the slot 8 and is formed **80** with a transversely extending opening 12 through which extends a wrist pin 13, the latter being mounted in the opening 7 formed in the tapered portion 3 of the core 1. The forward end of the head 11, of the **85** rod 6, is spaced from the base of the slot 8 thereby providing a clearance for the head 11 during the pivoting movements thereof.

Arranged within the forward end of the tapered portion 3, of the core 1, as well as **90** projecting forwardly from the latter is a peripherally threaded coupling member 14, having its rear end provided with a head 15 which abuts against the wall at the forward end of the slot 8. The member 14 extends **95** through the opening 9 and socket 10 and projects a substantial distance forwardly with respect to the forward end of the bore 1. The function of the coupling member 14 will be presently referred to. **100**

The tapered portion 3, of the core 1 may be of any desired length and diameter and it is adapted to have mounted thereon a set of expander elements. These elements can be 5 constructed of any suitable material and the number of elements of the set can be as desired, depending upon the length of the tapered portion 3. By way of example three expander elements are illustrated as arranged in enveloping position with respect 10 to the tapered portion 3 of the core 1. The expander elements are indicated at 16, 17 and 18. The outer diameter of each of the expander elements is the same. Each expander element is in the form of an annulus. The inner faces of each expander element conform in contour to the peripheral shape of the tapered portion 3 of the core 1. Under such conditions the inner face of each 15 expander element is tapered and by this arrangement each expander element has the body thereof gradually increasing in thickness in cross section from the follower face to the forward face of the element. The body portion of the element 18 is of less thickness than the body portion of the element 17 and the body portion of the latter is of less thickness than the body portion of the element 16. The outer sides of the expander elements 20 are flush with each other and the inner side of the expander element 16 forms a continuation of the inner side of the expander element 17 and the inner side of the expander element 17 forms a continuation of the inner 25 side of the expander element 18. As shown each of the expander elements is provided with a split and such split is indicated at 19 in Figure 5. It will be understood that the body portion of each expander element can be set up other than that as shown to provide 30 for the expansive characteristic of each element.

Associated with the expander elements is a set of shims and the shims of the set are 45 indicated at 20. Each of the shims is in the form of a ring and has the inner edge thereof bevelled and conforms to the contour of the tapered portion 3 of the core 1. Coacting with the set of shims to maintain the expander elements, in enveloping position with 50 respect to the tapered portions 3 of the core 1, is a retainer plate 21 having its outer diameter corresponding to the outer diameter of each of the expander elements and said plate is formed with a centrally arranged 55 opening 22. The coupling member 14 extends through the opening 22 and projects forwardly with respect to the plate 21. Coacting with the plate 21 for the purpose of 60 clamping it in position, whereby the plate in connection with the shims 20 will maintain the expanders in enveloping position with respect to the tapered portions 3 of the core 1, is a clamping nut or sleeve 23 which has 65 threaded engagement with the threads of the

coupling member 14 and is formed at its forward end with a laterally extending, annular flange 24 which overlaps the plate 21 whereby the latter is clamped in position.

It will be assumed that the normal position of the piston is as shown in Figure 1 and that it is desired to expand the same. When the piston is in normal position, the expander 16 has its forward face flush with the tapered portion 3 of the core 1. As illustrated by way of example four shims 20 are employed for the purpose of positioning the expander elements, so that the element 16 will have its forward face flush with the forward end of the tapered portion 3. Now it will be assumed that the piston is to be expanded. Two of the shims 20 are removed from the position as shown in Figure 1 and arranged around the forward end of the tapered portion 3. The retaining plate 21 is clamped in position and which forces the expander elements rearwardly upon the tapered portion 3, and causes the same to expand, whereby the diameter of the piston is increased to meet requirements.

In Figure 6 a modified form of expander element is illustrated, and which is indicated at 25. The outer periphery of the element 25 is formed with a groove 26 to receive a packing element or ring. Otherwise than that as stated the construction of the expander element 25 shown in Figure 6 is the same as that shown in Figures 1, 2 and 5.

The piston construction provides means whereby it can be expeditiously adjusted and expanded, when occasion requires and especially when the wall of a cylinder has become worn, under such conditions overcoming the necessity of the employment of an oversized piston and the re-boring of the cylinder wall. Furthermore the piston construction can be quickly and expeditiously assembled so that it can be employed with any desired size of cylinder, new or otherwise. Therefore it is thought the many advantages of an expandible piston, in accordance with this invention can be readily understood, and although the preferred embodiment of the invention is as illustrated and described, yet it is to be understood that changes in the details of construction can be had which will fall within the scope of the invention as claimed.

What I claim is:

1. In an expandible piston a core formed of a cylindrical portion, and a forwardly directed tapered portion of greater length and of less diameter throughout than said rear portion, said core having its rear end provided with a recess extending through said rear portion and into said tapering portion, said tapering portion formed at its axis with a rectangular, lengthwise extending slot, an opening and a socket, said opening interposed between and communicating with said socket and slot, said opening being of a diameter

less than that of the socket and less than the width of the slot, said tapering portion further formed with a diametrically extending opening intersected centrally thereof by said slot, and said slot opening into said recess and said socket opening at the forward end of said tapered portion.

2. In an extensible piston a core provided with means for receiving expander elements and further provided at its longitudinal median respectively with a rectangular slot to receive the head of the piston rod, an opening of less diameter than and communicating with the forward end of the slot, a socket communicating at its rear with said opening and a diametrically disposed opening intersecting said slot and adapted to receive a wrist pin for the piston rod head, combined with means for retaining the expander elements on the core and including a tubular element having a head positioned in the slot forwardly of the head of the piston rod, said element extending forwardly through said opening and socket.

25 3. In an expansible piston a core provided intermediate its ends and at its longitudinal median with a rectangular slot completely open at its rear and partly open at its forward end and providing for the reception of the head of a piston rod and for the head at the rear end of a forwardly directed anchoring means for retaining means for expander elements, and said core further formed with a diametrically disposed wrist pin receiving opening intersected transversely thereof by said slot.

4. In an expansible piston a core provided with means for receiving expander elements, said core formed at its forward end with a socket, at its rear end with a recess and in proximity and in advance of a diametrically disposed wrist pin receiving opening, said core further formed at its longitudinal median with a rectangular slot for receiving the head of a piston rod, said slot intersecting said opening, open at its rear end and communicating at its forward end with said socket, combined with a forwardly directed, headed anchoring element for a retaining means for the expander elements, said anchoring element extending through and projecting from said socket and having its head positioned in said slot and coacting with the forward end wall of the slot to retain it in the core, the head of the anchoring element positioned forwardly of the head of the piston rod.

In testimony whereof, I affix my signature hereto.

LEONARD C. BURNS.
